PUMP

Joseph A. Tennant and Herbert Allen, Houston,
Tex., assignors, by mesne assignments, to
Stephens Pump Company, Round Rock, Tex.,
a corporation of Delaware

Application May 14, 1934, Serial No. 725,566

12 Claims. (Cl. 103—44)

This invention relates generally to pumps.

It will be found particularly useful in pumps designed for pumping abrasive and corrosive fluid of the general type disclosed by Letters Patent of the United States to Stephens No. 1,848,441 of March 8, 1932. A conventional pump of this type adapted for use as a mud or slush pump in deep well drilling includes a barrel; inlet and outlet valves therefor; a hollow expansible member with-
5 in the barrel; and a reciprocable piston to actuate pumping fluid confined within the expansible member to cause expansion and contraction thereof whereby pumped fluid is drawn into and forced out of said barrel.

10 In pumps of other types the pumped fluid is in contact with the piston and rod and carries away the heat generated by the reciprocation of the piston and rod through conventional packings. In the type of pump to which this invention relates, however, the piston and rod are sealed off from the fluid being pumped and the heat so generated is therefore transferred to the pumping fluid within the expansible member. These expansible members are usually made of rubber, which 15 is a very good heat insulator, and the pumping fluid within the expansible member is in contact with very little metal. Under certain conditions, such as when the packings are inadvertently made too tight, the heat is not dissipated as rapidly as it is generated. And so, under such conditions, the pumping fluid in the expansible member will reach a very high temperature whereby the expansible member will be injured; and when the pressure on the pumping fluid is reduced on the 20 suction stroke of the piston, the pumping fluid will boil so that the pumping member will remain expanded, which renders the pump inoperative.

25 The present invention has for its general object the provision of new and improved means to prevent heating of the pumping fluid to an objectionably high temperature.

30 A specific object of the invention is the provision of means to cause the pumping fluid to be circulated by the piston through a cooler.

35 The pumped fluid is in most instances at a low enough temperature to be used as a cooling medium, and this invention has for another of its specific objects the utilization thereof as such, the heat of the pumping fluid being transferred by the means provided to the pumped fluid.

40 Pumps of this type are adapted to pump fluid under very high pressures, and another specific object of the invention is to provide a cooler constructed and disposed in a new and improved manner so that the pressure differential across the

walls thereof shall be very small, whereby said walls may be made sufficiently thin to permit the pumped fluid to readily cool the pumping fluid, without danger of failure and consequent leakage.

Other objects will hereinafter appear.

5 The preferred embodiments of the invention are illustrated by the accompanying drawings, wherein Fig. 1 is a sectional elevation of one of the barrels of the pump equipped with the cooler; Fig. 2 is a fragmentary view illustrating the sleeve which may be added to the pump to assist in forcing the pumping fluid out of the expansible member into the cooler; Fig. 3, a view similar to Fig. 1 of another embodiment; and Fig. 4, a fragmentary view taken at a right angle to Fig. 3.

10 As the operation of pumps of this type is clearly set forth in the said patent to Stephens, No. 1,848,441, it will be but briefly referred to here as follows:

15 In the drawings the barrel is indicated at 1, and the inlet and outlet means at 2 and 3, the latter including valves not shown. Within the barrel 1 is a hollow expansible member 4 which may comprise a rubber sleeve having an internal annular flange 5 secured to one end wall of the 20 barrel 1 by the ring 6; and an external annular flange 7 secured to the other end wall of the barrel 1 by a ring 8. The numeral 9 indicates the piston which is reciprocated by means not shown to actuate the pumping fluid within the 25 expansible member 4 to draw the pumped fluid into the barrel 1 through the inlet means 2, and to expel it from the barrel 1 through the outlet means 3. When the piston 9 is at the end of its suction stroke as shown by the solid lines, the 30 shape of the expansible member 4 is substantially cylindrical, and the barrel 1 is filled with pumped fluid. When the piston 9 moves to the right on its discharge stroke into its broken line 35 position 9a in the expansible member 4, it displaces the pumping fluid in said expansible member, and causes said expansible member to expand into the shape indicated by the broken line 4a. During such expansion the inlet valve (not shown) of the means 2 remains closed, and the outlet valve (not shown) of the means 3 opens to permit the pumped fluid to be expelled from the barrel 1 through the outlet means 3. Now when the piston moves on its suction stroke 40 from its broken line position 9a to its solid line 45 position 9, the expansible member contracts from its expanded broken line shape 4a into its contracted solid line shape 4; and as the valve (not shown) of the outlet means 3 then remains closed, and the valve (not shown) of the inlet 50

means 2 opens, a fresh charge of pumped fluid is thereby drawn into the barrel 1. It will be obvious that as the piston 9 reciprocates, the pumped fluid will be alternately drawn into and expelled from the barrel.

5 The means whereby the ends of the expandable member 4 are sealed to the barrel 1, and the piston 9 is packed, may, of course, be varied without departing from the present invention.

10 The construction herein disclosed for that purpose will form the subject matter of another application.

Referring now to the new and improved means provided by this invention for the purposes above set forth, it will be noted that a pumping fluid cooler 10 is disposed in the inlet means 2 in the path of the pumped fluid passing through said inlet means into the barrel 1, and that this cooler is connected by the pipe 11 and duct 12 to one end of the expandable member 4; and by the pipe 13 and duct 14 to the other end of the expandable member 4. It will be seen that the ring 8 is provided with suitable ducts so that the fluid may pass from the duct 12 into the 25 adjacent end of the expandable member 4; and that the ring 6 has a central opening through which the fluid may pass from the expandable member 4 into the duct 14. The numeral 15 indicates a check valve in the pipe 13 opening 30 in the direction indicated by the arrow.

Now as the piston moves from its solid line position 9 into its broken line position 9a on its discharge stroke, the pumping fluid in the expandable member 4 is agitated and a portion of 35 it is forced ahead of the piston and through the duct 14, check valve 15, cooler 10, and then back through pipe 11 and duct 12 into the other end of the expandable member 4. And when the piston moves from its broken line position 9a into 40 its solid line position 9, on its suction stroke, the pumped fluid is drawn through the inlet means 2 into the barrel 1. The pumping fluid is thereby subjected to the cooling action of the pumped fluid, the latter of which flows over the cooler 10 as it passes through the inlet means 2 into the barrel 1. It will be understood that 45 as the piston 9 reciprocates, the pumping fluid is made to circulate through the cooler 10, and is thereby kept cool by the pumped fluid.

50 Referring to Fig. 2, corresponding numerals indicate like parts, but the ring 6 has been omitted and in its place is a ring 6a. Integral with the ring 6a is an inwardly presented sleeve 16, the internal diameter of which is such that it 55 snugly receives the piston 9 during the latter part of the piston's discharge stroke to assist in causing the movement of the pumping fluid from the expandable member 4 through the duct 14 and pipe 13 into the cooler. It will be understood that in this figure the piston 9 is shown 60 near the end of its discharge stroke, and the expandable member in its expanded shape.

In Figs. 3 and 4 the elements correspond with the elements shown by Fig. 1, except that a different embodiment of the cooler is provided. In this embodiment the inlet means 2 includes an elongated port 2a extending substantially along the length of the barrel 1 to introduce the pumped fluid in a direction substantially tangential to the inner surface 17 of the barrel; and the barrel is provided with a similarly elongated pumping fluid passageway 18 communicating with one end 65 of the expandable member 4 through the ducts 19 and 20 and check valve 21; and with the other

end of the expandable member through the duct 22 and the ducts in ring 8. As the pumped fluid exerts an outward pressure on the inner wall 23 of the passageway 18, and the pumping fluid exerts an inward pressure on said wall, and said pressures are substantially the same, the pressure differential across the said wall 23 is very small, and it may be made relatively thin to enable the pumped fluid to readily cool the pumping fluid without danger of failure and consequent leakage. The wall 23 is also directly in the path of the pumped fluid issuing at a high velocity from the inlet port 2a, so that the cooling action of the pumped fluid is most efficiently utilized.

This invention is not limited to the preferred 15 embodiments herein disclosed. Various changes will occur to those skilled in the art, and may be made within the scope of the following claims.

We claim:

1. A pump having a barrel; inlet and outlet means for said barrel; a hollow expandable pumping member sealed in said barrel; pumping fluid in said member; a piston reciprocable in said member to effect the expansion and contraction of said member to draw pumped fluid into said barrel through said inlet means, and to expel it from said barrel through said outlet means; said inlet means including an elongated port to introduce the pumped fluid in a sheet substantially tangential to the inner surface of said barrel; a pumping fluid cooler comprising an elongated pumping fluid passageway in the body of said barrel and communicating with the opposite ends of said member; the inner wall of said passageway being disposed in the path of the pumped fluid entering said barrel through said inlet port; and a check valve between said cooler and that end of said member toward which said piston moves on its discharge stroke; said piston serving to cause said pumping fluid to circulate thru said 40 cooler.

2. A pump having a barrel; inlet and outlet means for said barrel; a hollow expandable pumping member sealed in said barrel; pumping fluid in said member; a piston reciprocable in said member to effect the expansion and contraction of said member to draw pumped fluid into said barrel through said inlet means, and to expel it from said barrel through said outlet means; said inlet means including an elongated port to introduce the pumped fluid in a direction substantially tangential to the inner surface of said barrel; a pumping fluid cooler comprising an elongated pumping fluid passageway in the body of said barrel and communicating with the opposite ends 55 of said member; the inner wall of said passageway being disposed in the path of the pumped fluid entering said barrel through said inlet port; and a check valve to permit said fluid to circulate thru said cooler in but one direction; said piston 60 serving to cause said pumping fluid to circulate thru said cooler in said direction.

3. A pump having a barrel; inlet and outlet means for said barrel; a hollow expandable pumping member sealed in said barrel; pumping fluid in said member; a piston reciprocable in said member to effect the expansion and contraction of said member to draw pumped fluid into said barrel through said inlet means, and to expel it from said barrel through said outlet means; and a pumping fluid cooler comprising an elongated pumping fluid passageway in the body of said barrel and communicating with the opposite ends of said member; the inner wall of said passageway being disposed in the path of the pumped 75 fluid.

fluid entering said barrel through said inlet means; said piston serving to cause said pumping fluid to circulate thru said cooler.

4. A pump having a barrel; inlet and outlet means for said barrel; a hollow expansible pumping member sealed in said barrel; pumping fluid in said member; means to actuate said pumping fluid to effect the expansion and contraction of said member to draw pumped fluid into said barrel through said inlet means, and to expel it from said barrel through said outlet means; and a pumping fluid cooler comprising a pumping fluid passageway in the body of said barrel and communicating with the opposite ends of said member; the inner wall of said passageway being disposed in the path of the pumped fluid in said barrel.

5. A pump having a barrel; inlet and outlet means for said barrel; a hollow expansible pumping member sealed in said barrel; pumping fluid in said member; a piston reciprocable in said member to effect the expansion and contraction of said member to draw pumped fluid into said barrel through said inlet means and to expel it from said barrel through said outlet means; a pumping fluid cooler in the path of the pumped fluid adjacent said inlet and communicating with opposite ends of said expansible member, and a check valve to permit the circulation of said pumping fluid thru said cooler in but one direction; said piston serving to cause said pumping fluid to circulate thru said cooler.

6. A pump having a barrel; inlet and outlet means for said barrel; a hollow expansible pumping member sealed in said barrel; pumping fluid in said member; a piston reciprocable in said member to effect the expansion and contraction of said member to draw pumped fluid into said barrel through said inlet means and to expel it from said barrel through said outlet means; and a pumping fluid cooler in the path of the pumped fluid and communicating with opposite ends of said expansible member; said piston serving to cause said pumping fluid to circulate thru said cooler.

7. A pump having a barrel; inlet and outlet means for said barrel; a hollow expansible pumping member sealed in said barrel; pumping fluid in said member; a piston reciprocable in said member to effect the expansion and contraction of said member to draw pumped fluid into said barrel through said inlet means and to expel it from said barrel through said outlet means; and a pumping fluid cooler communicating with said expansible member; said piston serving to cause said pumping fluid to circulate thru said cooler.

8. A pump having a barrel; inlet and outlet means for said barrel; a hollow expansible pumping member supported by and sealed in said

barrel; pumping fluid in said member; means to actuate said pumping fluid to effect the expansion and contraction of said member to draw pumped fluid into said barrel thru said inlet means and to expel it from said barrel thru said outlet means; and a pumping fluid cooler and closed means for conducting said pumping fluid from said member to said cooler and back again.

9. A pump having a barrel; inlet and outlet means for said barrel; a hollow expansible pumping member sealed in said barrel; pumping fluid in said member; a piston reciprocable in said member to effect the expansion and contraction of said member to draw pumped fluid into said barrel through said inlet means and to expel it from said barrel through said outlet means; a pumping fluid cooler communicating with said expansible member; said piston serving to cause said pumping fluid to circulate thru said cooler; and a sleeve constructed and arranged for the snug reception of said piston during the latter part of its discharge stroke to assist in causing the movement of said pumping fluid into said cooler.

10. A pump having a barrel, inlet and outlet means for said barrel, a hollow expansible pumping member supported by and sealed in said barrel, pumping fluid in said member, means to actuate said pumping fluid to effect the expansion and contraction of said member to draw pumped fluid into said barrel through said inlet means, and to expel it from said barrel through said outlet means, and pumping fluid cooling means connected to the opposite ends of said expansible member including a heat-transferring portion located adjacent said inlet means.

11. A pump having a barrel, a hollow expansible pumping member supported by and sealed in said barrel, pumping fluid in said member, means to actuate said pumping fluid to effect the expansion and contraction of said member to draw pumped fluid into and to expel it from said barrel, a cooler in the path of the pumped fluid, and means for circulating the pumping fluid from said member through said cooler and back into said member.

12. A pump having a barrel, a hollow expansible pumping member supported by and sealed in said barrel, pumping fluid in said member, means to actuate said pumping fluid to effect the expansion and contraction of said member to draw pumped fluid into and to expel it from said barrel, and means for circulating the pumping fluid from said member through the pumped fluid and back into said member.

JOSEPH A. TENNANT.
HERBERT ALLEN.
